Primary Examiner — Mary Ann Calabrese(74) Attorney, Agent, or Firm — NSIP LawCLAIM

The ornamental design for a display screen or portion thereof with graphical user interface, as shown and described.

DESCRIPTION

The FIGURE is a front view of a display screen or portion thereof with graphical user interface, showing my new design.

The broken lines along the perimeter represent a display screen or portion thereof and form no part of the claimed design. All other broken lines are for illustrative purposes only and form no part of the claimed design.
